ABRAHAM TRAUBE, OF BROOKLYN, NEW YORK.

DRY-CLEANING APPARATUS.

1,291,266.

Specification of Letters Patent. Patented Jan. 14, 1919.

Application filed January 9, 1918. Serial No. 210,985.

To all whom it may concern:

Be it known that I, ABRAHAM TRAUBE, a citizen of the United States of America, residing at 1418 Cortelyou road, Brooklyn, New York, have invented new and useful Improvements in Dry-Cleaning Apparatus, of which the following is a specification.

My invention relates to an apparatus for dry cleaning fabrics, such as clothes, garments or the like, by means of volatile solvents.

An object of my invention is the provision of a clothes cleaning apparatus having means associated therewith for rendering the application of the solvents, their recuperation and all intermediate steps, continuous and automatic, so that without the aid of an attendant, a garment may be repeatedly treated for predetermined intervals 20 with the same supply of solvents.

Another object of my invention is the provision of a system of supplying the solvents to and withdrawing the same from a clothes cleaning apparatus, and means for maintaining a vacuum within the apparatus at all times to prevent escapement of gases from the apparatus, whereby the gases emanating from the solvents will be automatically collected and prevented from escaping to the atmosphere, thereby eliminating any chances 30 of fire or injury to the operator of the apparatus by inhalation of the gases.

I will describe one form of apparatus and system embodying my invention, and will 35 then point out the novel features thereof in claims.

In the accompanying drawings the figure is a view showing in side elevation one apparatus embodying my invention.

Similar reference characters refer to similar parts in each of the several views.

Referring to the drawings, 10 designates a platform upon which is mounted the cleaning apparatus, generally indicated at 45 A. In the present instance, the cleaning apparatus comprises a cylindrical air-tight tank 11 mounted upon supporting standards 12, and a rotatable drum 13 mounted within the tank 11. The drum 13 is of the usual construction, it being formed of longitudinally extending spaced ribs 14, so that the detergent liquids or solvents contained within the tank may pass freely through the drum and on to the garments contained 50 within the drum. As shown, the drum is fixed to a shaft E, the opposite ends of which

are journaled in the tank 11. For the purpose of heating the interior of the tank 11, the apparatus A is provided with a heating coil 15, to which steam or any other heating agent is supplied, by means of a pipe 16. The heating agent is supplied to the pipe 16 by means of a branch pipe 17 controlled by a valve 18, and withdrawal of the heating agent from the coil is effected by means of 60 a branch pipe 19 controlled by a valve 20. For the purpose of cooling the interior of the apparatus A, such apparatus is provided with a cooling coil 21, shown in dotted lines in Fig. 1. This coil is supplied with a cooling agent by means of a pipe 22, the supplying and withdrawal of the cooling agent being effected by pipes 23 and 24 respectively, controlled by valves 25 and 26 respectively. 70

The apparatus A is connected by means 75 of pipes 27 and 28 with a reservoir R, such reservoir containing one of the solvents, such as benzin, employed in the cleaning apparatus. The reservoir R is at a lower level than the apparatus A, the pipe 27 being 80 connected to the underside of the tank 11, through the medium of a sediment catching receptacle 29. By means of a pipe 81, controlled by a valve 80, ammonia gas, constituting another cleaning agent, is fed to tank 85 11 from a tank T mounted on a platform 42.

For draining the tank 11 of the solvents after each cleaning operation, I provide two storage receptacles D and D', which are supported upon a platform 42 and which are 90 connected to pipe 27 through the medium of a pipe 30 and branch pipes 31 and 32. At the intersection of the pipes 31 and 32 and the pipe 30, I provide a valve 33. This valve 33 is a two-way valve and 95 when in the position shown, it connects pipe 30 with pipe 31, and when in the position shown in dotted lines, it connects pipe 32 with pipe 30. At the intersection of pipes 27, 28 and 30, I provide another valve 34 100 which is capable of occupying two extreme positions and an intermediate position, and connects pipe 27 with pipe 30 or 28, according as it occupies one extreme position or the other, and disconnects pipe 27 from 105 these pipes when in the intermediate position.

For the purpose of removing residue gases from the apparatus A, I provide an exhaust pipe 35, the upper end of which 110 communicates with the upper side of the tank 11, while the lower end thereof is con-

nected to a condenser C. This condenser C is of the usual construction, it being provided with inlet and outlet pipes 36 and 37 respectively, for circulating a cooling medium about a coil of pipe 38 which has its upper end connected to pipe 35, while its lower end communicates with a discharge pipe 39, which latter is in turn connected to a vacuum pump P. The pump P is driven by the shaft 51 through a belt 92, as shown; and is designed for the purpose of creating a vacuum in the exhaust pipe 35 and consequently in the tank 11, thereby removing residue gases from the tank and 10 passing the same through the condenser C whereby such gases will be condensed and again used. The vacuum pump P is provided with a discharge pipe 40, which communicates with a main discharge pipe 41, whereby the condensed gases may be conveyed to a clarifier B disposed below the lower platform 42. The clarifier B is connected with the reservoir R by a pipe 90, as shown.

25 The exhaust pipe 35 is provided with a branch pipe 43, and the passage of gases through the pipes 35 and 43 is controlled by a two-way valve 44, disposed at the intersection of the two pipes. The pipe 43, in turn, communicates with two branch pipes 45 and 46, and the passage of liquid or gases from pipe 43 to pipes 45 and 46 is controlled by a two-way valve 47. The pipe 45 communicates with the storage receptacle D', while pipe 46 communicates with the storage receptacle D. Communicating with the bottom of the receptacles D and D' are pipes 48 and 49 respectively, which pipes are connected to the main discharge pipe 41, and the passage of solvents through this pipe is controlled by a two-way valve 50. As previously stated, the discharge pipe 41 communicates with the clarifier B, and the latter is in turn connected with the main 45 reservoir tank R.

In carrying out my invention, I provide mechanism for automatically rotating the drum 13 a predetermined number of revolutions in one direction, and then stopping and 50 rotating the same a predetermined number of revolutions in the opposite direction. This mechanism, as here shown, comprises a main power shaft 51, journaled in bearings 52 which depend from the under side of the 55 platform 10. Arranged upon the platform 10 is a driven shaft 53 journaled in bearings 54 and operatively connected to the power shaft 51 by means of a belt 55. The shaft 53 is provided with a loose pulley 57, a fixed 60 pulley 56, and an idle pulley 58 interposed between the two. Fixed to and rotatable with the pulley 57 is a beveled gear 57^a which constantly meshes with another beveled gear 57^b supported on a suitable 65 bracket, as shown. The gear 57^b in turn

meshes with a beveled gear 57^c which is fixed to the shaft 53. It will thus be seen that when the pulley 56 is driven in one direction, the shaft 53 is rotated in the corresponding direction, and when pulley 57^b is driven in the same direction as pulley 56, shaft 53 is driven in the opposite direction through the beveled gears 57^a, 57^b, and 57^c. A belt 55 is trained over a pulley 59 fixed to the shaft 51, such pulley being elongated 75 to permit lateral shifting of the belt thereon. As shown in the figure, the belt normally passes around the idle pulley 58 so that motion is not imparted to the drive shaft 53. However, by means of a shifting device 60, the belt may be shifted to engage either pulley 56 or 57 so as to rotate the shaft 53 in one direction or the other. The shifting device 60 may be operated automatically to reverse the direction of 85 the rotation at predetermined intervals, however, to simplify the drawings, I have not shown such means. For driving the drum 13 at a relatively slow speed, a small pinion 61 is fixed to the shaft 53 and meshes 90 with a relatively large gear 62 fixed to a shaft E.

To effect an automatic operation of the entire system for supplying solvents to the cleaning apparatus A, and for recuperating the same, I provide mechanism for continuously operating the various valves at predetermined intervals and in proper sequence, thereby rendering the apparatus wholly automatic in operation and thus 100 eliminating the necessity of an attendant. In the present instance, this end is accomplished by operating all of the valves by cams K, such cams being fixed to a shaft 63 journaled in hangers 64 suspended from the platform 10. The shaft 63 is driven at a predetermined slow speed by the shaft 51, through the medium of a beveled pinion 93 fixed to the shaft 51 and meshing with a large beveled gear 94 fixed to one end of a 105 pintle 95, the opposite end of the pintle being provided with a worm 96 meshing with a worm gear 97 fixed to shaft 63. Each valve is provided with an arm 65 to which is pivotally connected one end of a 110 rod 66, while the opposite end of such rod is arranged to contact at all times with the surface of its corresponding cam K. The rods 66 disposed above the cam shaft 63, constantly engage the surfaces of their cams 115 K at all times, by the action of gravity, while the rods disposed below the cam shaft are maintained in engagement with their cams by means of contractile springs 67. The valves 33 and 47 are adapted to be operated simultaneously with the operation of valve 50, by means of a link 68 connecting the arms 65 of the valves 33 and 47, and an arm 69 formed on valve 33 and pivotally connected to the rod 66 of valve 50. All 120 125 130

of the cams K, with the exception of the cam for operating valve 34, are formed with two cam surfaces so arranged as to operate corresponding valves at a predetermined time, while the cam for the valve 34 is provided with three cam surfaces to move the valve from the position shown in the drawing to either of the positions shown in dotted lines.

10 From the foregoing description, taken in conjunction with the accompanying drawings, the operation of the cleaning apparatus and mechanism will be apparent as follows: The clothes or garments to be cleaned are placed within the drum through air-tight doors (not shown) formed on the tank and drum respectively. Power is now applied to the main shaft 51 so that it is continuously rotated in the direction of the arrow. At the beginning of every cleaning operation, all of the valves occupy the positions shown in Fig. 1 and which I term the normal positions. By means of the slowly rotating shaft 63, exhaust pipe 35 is now connected with the vacuum pump P, by movement of valve 44 to the position shown in dotted lines, whereupon the air in tank 11 is withdrawn through pipe 35, condenser C, pump P, and pipes 40 and 41 to atmosphere. With the exhaustion of air from tank 11, a suction is created in pipe 28 thereby drawing the cleaning solvent from the reservoir tank R into tank 11. After a predetermined quantity of the solvent has entered the tank 11, the valve 34 returns to its intermediate position, thus discontinuing the supply of solvent to the tank. Pump P, however, remains connected with tank 11 and thus continues to withdraw all vapors or gases from the tank during the cleaning operation, whereby a constant vacuum therein is always maintained. This is a very important feature of my invention, as by continuously withdrawing all gases from the cleaning apparatus, any possibility of gases escaping from the apparatus to cause explosion or injury of an attendant by inhalation of such gases is eliminated. During intake of the solvents into tank 11, from reservoir R, valve 80 is opened for a short interval, thus admitting ammonia gas to tank 11 from tank T, the same intermixing with the other solvents and thereby producing an efficient cleaning mixture.

55 The solvent mixture now having been supplied to the cleaning apparatus, the drum 13 is operatively connected with the drive shaft 51 to effect rotation thereof first in one direction and then the other, by shifting of the belt 55, as has been explained. The movement of the drum 13 causes the clothes to be bathed in the solvent mixture, in a manner well understood in the art. After this operation has continued for a specified time, during which a constant vacuum is

maintained in the cleaning apparatus, the pipe 27 is connected with pipe 30 by movement of valve 34 to its upper extreme position, and pipe 35 is disconnected from pump P and connected with pipe 43 by movement of valve 44 to its normal position. As a result, the solvent mixture drains from tank 11 into pipe 27 and then into pipe 30. With the valves 33 and 47 occupying the position shown, communication between pipes 30 and 43 and the receptacle D' is established by pipes 32 and 45 respectively, thus allowing the used mixture to pass into the receptacle D'. However, as valve 50 occupies the position shown in the drawings, pipe 49 is disconnected from pipe 41 and atmosphere, so that the receptacle D' is maintained air-tight and the emptying of the same prevented. By this arrangement, I produce a completely closed vacuum circuit, which circuit is as follows: The tank 11, pipes 27, 30 and 32, receptacle D', pipes 45, 43 and 35 back to tank 11. This vacuum circuit permits draining of the tank 11, at the same time maintaining a constant vacuum in the tank and thus preventing the escape of gases from any part of the system.

After the drainage of tank 11 has been thoroughly effected, the same cycle of operations is repeated for the next cleaning operation. At that period in the second cleaning operation, when the used solvent and gases are admitted to pipes 30 and 43 respectively, valves 33 and 47 have been moved to occupy the positions shown in dotted lines, wherein pipes 30 and 43 are connected to pipes 31 and 46 respectively, thus allowing the solvents and gases to pass into receptacle D. Upon movement of valves 33 and 47 to the positions shown in dotted lines, valve 50 is also moved to its dotted line position, so that pipe 49 is connected with pipe 41. The used solvents in receptacle D' now pass to the clarifier C where they are filtered and returned to reservoir R through pipe 90. It will thus be seen that as receptacle D' is being filled, receptacle D is being emptied and that the emptying of receptacle D' does not disturb the closed vacuum circuit now including receptacle D, thereby maintaining the vacuum in tank 11. From the foregoing it will be manifest that the used solvent mixture is deposited in one of the receptacles during one cleaning operation and in the other receptacle during the next cleaning operation, and that when either receptacle is being filled, the other is being emptied.

After the predetermined number of cleaning operations have been completed, and the tank 11 has been properly drained, the valve 18 is opened, thus admitting steam to coil 15. The valve 18 remains open for a predetermined interval during which the clothes are thoroughly dried. Just before the drying operation is completed, the valve 18 is closed

and the valve 20 is opened, thus exhausting the steam from the coil 15 through pipe 19. Simultaneously therewith, valve 25 is opened to admit a cooling agent to coil 21, thereby cooling the apparatus for the next lot of clothes.

It will be apparent from the above description that garments or clothes may be subjected to any desired number of cleaning operations, without the constant attention of an operator, thus rendering it possible for a single operator to control a plurality of cleaning machines of this character.

Although I have herein shown and described only one system, one form of cleaning apparatus and mechanism, it will be understood that various changes and modifications may be made therein without departing from the spirit and scope of the appended claims.

What I claim is:

1. In combination, a cleaning apparatus, means for conveying a solvent to said apparatus, a receptacle for receiving the used solvent from said apparatus, a closed pipe circuit including said apparatus and said receptacle, and means for creating a vacuum in said circuit.

2. In combination, a cleaning apparatus, means for conveying a solvent to said apparatus, a receptacle for receiving the used solvent from said apparatus, a closed pipe circuit including said apparatus and said receptacle, means for creating a vacuum in said circuit, and means for maintaining said vacuum in said circuit when said vacuum creating means is disconnected from said circuit.

3. In combination, a cleaning apparatus, means for conveying a solvent to said apparatus, a pair of receptacles for receiving the used solvent from said apparatus, means for separately emptying said receptacles, a closed pipe circuit including said receptacles, and means for disconnecting either receptacle from said pipe circuit when the same is being emptied.

4. In combination, a cleaning apparatus,

a receptacle, a closed pipe circuit including said apparatus and said receptacle, means for creating a vacuum in said circuit, a solvent reservoir, a branch pipe connecting said solvent reservoir and said circuit, and means for establishing communication between said circuit and said branch pipe to utilize the vacuum in said circuit to draw the solvent from said reservoir into said apparatus.

5. A cleaning apparatus, comprising a tank, means for producing a vacuum for introducing a solvent into said tank and removing the solvent and residue gases from said tank, and mechanism for controlling said means and for rendering the operation thereof continuous and in proper sequence.

6. A cleaning apparatus comprising a tank, a cleaning drum, means for introducing a predetermined quantity of solvent into said tank, means for withdrawing said solvent from said tank after a predetermined interval, and means for withdrawing the solvent vapors from said casing.

7. A cleaning apparatus comprising a tank, means for introducing a solvent into said tank, means for recuperating said solvent subsequent to the cleaning operation, and cam operated means for controlling the last mentioned means.

8. A cleaning apparatus comprising a tank, means for introducing a solvent into said tank, means for removing said solvent after a predetermined interval, means for heating said tank for a predetermined interval subsequent to the withdrawal of said solvent, and means for cooling said tank.

9. In combination, a cleaning apparatus, means for introducing a solvent into said apparatus and for recuperating the same after the cleaning operation, and means for maintaining a vacuum in said apparatus prior to, during, and subsequent to the cleaning operation.

In testimony whereof I have signed my name to this specification.

ABRAHAM TRAUBE.
